Primary Examiner — Melanie H Tung*(74) Attorney, Agent, or Firm* — Fiala & Weaver P.L.L.C.**(57) CLAIM**

The ornamental design for a graphical user interface for a display screen or a portion thereof, as shown and described.

DESCRIPTION

The single FIGURE is a front view of a graphical user interface for a display screen or portion thereof.

The broken line showing of the display screen or portion thereof in the FIGURE is not part of the claimed design.

1 Claim, 1 Drawing Sheet
